UNITED STATES PATENT OFFICE

HENRY A. PETER, OF PHILADELPHIA, PENNSYLVANIA, ASSIGNOR TO PIONEER SUS-PENDER COMPANY, A CORPORATION OF PENNSYLVANIA

DESIGN FOR A GARTER

Application filed April 26, 1932. Serial No. 43,616. Term of patent 14 years.

To all whom it may concern:

Be it known that I, HENRY A. PETER, a citizen of the United States, residing at Philadelphia, in the county of Philadelphia, State of Pennsylvania, have invented a new, original, and ornamental Design for a Garter, of which the following is a specification, reference being had to the accompanying drawing, forming part thereof.

The figure is a view in elevation of a garter embodying the design.

I claim:—

The ornamental design for a garter as shown.

HENRY A. PETER.
